UNITED STATES PATENT OFFICE.

JOHN P. PROBST, OF MARION, OHIO.

CISTERN.

Application filed February 23, 1922. Serial No. 538,425.

To all whom it may concern:

Be it known that I, JOHN P. PROBST, a citizen of the United States, residing at Marion, in the county of Marion and State of Ohio, have invented certain new and useful Improvements in Cisterns, of which the following is a specification, reference being had therein to the accompanying drawing.

This invention relates to improvements in cisterns in which rain water is received from the roofs of houses and buildings.

The prime object of the invention is to prevent the inflow of the water into the cistern from stirring up the sediment and dirt which collect at the bottom of the cistern, a prevailing objection to the use of cisterns being that sediment or dirt pass from the cistern into the supply pipes leading to the houses or buildings.

This object is accomplished by placing within existing cisterns a sub-cistern or supplemental vessel, or by building new cisterns in the form of a main vessel and a supplemental vessel within it, so that the water is received from the down spout first into the sub-cistern or supplemental vessel from which it flows over a wide margin compared with the area of the inlet. In this way the speed of the incoming water is reduced and it simply overflows the margins of the sub-cistern or supplemental vessel, thence into the main cistern without violently agitating the contents of the latter.

In the accompanying drawings,

Fig. 1 is a vertical sectional view of a cistern constructed in accordance with my invention;

Fig. 2 is a plan view of the supplemental cistern alone;

Fig. 3 is a vertical sectional view of the same on the line 3—3 of Fig. 2;

Fig. 4 is another sectional view on the line 4—4 of Fig. 2, the shell of the supplemental cistern being sectioned and the supply conduit and discharge pipe in elevation.

Fig. 5 is a detail sectional view showing the connection between the supplemental cistern and the discharge pipe.

In carrying out my invention I construct a cistern in any usual and approved manner, as of brick or cement, as shown at 1, and locate the same under ground in a common manner. If such a cistern is already erected or in use I build or place within it my supplemental cistern, or if the whole struc-

ture is to be erected at once I build the cistern proper and at the same time also build the supplemental cistern or otherwise place it in the main cistern. In either event I have a main cistern 1 and a supplemental 60 cistern 2.

The main cistern has the usual man-hole indicated at 3 with a convenient cover, such as shown at 4. Into this cistern leads a supply pipe 5 which connects with a down 65 spout 6. The supply pipe 5 discharges into a conduit 7 which extends to and discharges into the supplemental cistern. A thimble 8, preferably made of cast iron, receives or makes connection with the conduit 7 and is 70 mounted on and fitted to the supplemental cistern by having its flange 9 rest on the adjacent walls 11 of the supplemental cistern.

The supply pipe 5 and conduit 7 are preferably constructed of cast iron soil pipe 75 which, when the sections are united, are self sustaining in the sense that a pipe so built up becomes rigid and firm. In the bell 12 I place a layer of oakum, occupying about half of the bell and then caulk the remainder 80 of the joint with lead or cement, as indicated at 14.

Referring now more particularly to the features which characterize the supplemental cistern it will be observed from Fig. 2 85 that it is widened out, as shown at 13. The walls slope downwardly and inwardly from the margin after the fashion of a bowl. It will be noted that the length of the overflow line, the upper edge of the enlarged portion, 90 is very much greater than the circular dimension of the inflow for the water. In this way the water is allowed to spread out, as it were, so that its velocity of discharge from the supplemental cistern is very slow 95 compared with the velocity of the inflow of the water. In this way the "rush" of the water is eliminated and by the action of the gentle overflow the sediment which has gathered in the bottom of the main cistern 100 will be disturbed little or none. In this way I make a broad provision for drawing off the water in a clear state notwithstanding that sediment and dirt will inevitably gather in the bottom of the main cistern.

The supplemental cistern is further characterized by an inwardly extended portion 13^a, as seen best in Fig. 1. The water coming into this vessel contacts with this inwardly extended portion and thereby has 110

its velocity broken and is caused to sweep over this curvature, resulting in an even and smooth overflow around the entire periphery of the supplemental cistern. This portion 5 13^a I term a water deflecting surface.

And then I supplement this manner of getting clear water by the several devices now to be mentioned with reference to the mode of drawing the water from the cistern. 10

Along the margin of the supplemental cistern I form projections 14 spaced apart so that any floating objects on the water, when the water line is slightly above the top line of the supplemental cistern, will 15 be obstructed and prevented from flowing into the supplemental cistern as the water line lowers from point to point.

Again, when the water line shall have dropped below the upper margin of the supplemental cistern the supply from the main cistern to the supplemental will be through the opposite passages 15, formed between an outer skirt 16 and the part 16^a of the wall of the supplemental cistern. The skirt projects below the upper edge of this wall so 20 that the re-entering water—that which flows from the main into the supplemental cistern—must pass below this skirt and thence rise upward and pour over the wall 16^a, 25 whereby such re-entering water is thoroughly skimmed of floating particles.

Referring now to the house supply pipe by which the water is delivered from the cistern to the places of use it will be seen 30 that I have connected such pipe, 18, to the supplemental cistern. See Fig. 5 in particular. Any means of forming this connection may be employed, such as a bushing 19 screwed into an opening in the wall and 35 adapted to receive a section of the pipe 18, which after extending a short distance laterally extends upwardly through the main cistern until it branches off at a convenient 40 point below the frost line, as indicated at 45 20 in Fig. 1.

The entrance end of the discharge pipe 18 is, in effect, downward by reason of the presence of a cap 21 secured to the wall of the supplemental cistern. This cap extends 50 below the entrance end of the pipe 18, as indicated at 22, for the purpose of preventing foreign matter, such as chips or leaves, from entering this discharge or suction pipe at times when the water level in the sub-cistern 55 is about in line with such pipe. Such foreign matter, if drawn up into the pump connected with the pipe 18 is practically certain to lodge under the check valve and interfere with the operation of the pump. 60 It will also tend to clog up the pipe 18.

In order to prevent the possibility of such or any foreign matter entering the pipe 18 by being drawn or sucked into it under the lower edge of the cap when the water level 65 is but little below such edge, I provide one

or more perforations 23 in the cap to allow the inrush of air into the pipe 18, to destroy the action of the pump, at times when the water is approaching a level so low with respect to the cap as would permit the drawing in of any such foreign matter. Before 70 that stage is reached air entering the perforations 23 will arrest the pumping action.

From the foregoing description and the accompanying drawings, it will be understood and appreciated that by my invention I am able to receive the water into the cistern with the usual rush and violence with which it enters, yet that I so slow down the speed of movement of the water that when it reaches the cistern proper it enters quietly and almost calmly so that it does not disturb the sediment which has collected at the bottom. 75

It will also be understood that I draw 80 the water from the inner or supplemental cistern within which there is practically no sediment as the sediment lodges in the outer or main cistern where there is neither material motion due to inflow or outflow. The 85 sediment collecting, as it does, outside the inner vessel, makes the inner vessel the available place from which to draw off the supply for use. The point of inflow from the outer to the inner vessel through the passages 15 which are elevated far enough 90 above the bottom of the outer vessel to be above the line of accumulated sediment, is such that the water which so inflows is practically free of sediment. 95

Thus, the inner vessel is a place where the rush of the incoming water is broken, as also a place where sediment does not collect and hence is the advantageous place from which to draw off the water for use. 100

I would have it understood that I regard myself as being the first to discover and create this system of managing water in the process of filling cisterns. 105

Another advantage in the use of my dual 110 or two-chamber cistern is that the water being kept clean will not clog up filters when they are used to clarify and eliminate from the water the fine particles which are in suspension. What might be called dirt or mud 115 being eliminated from the supply line, the water goes clear and free of such foreign matter to the filters.

Having thus fully described my invention, what I claim as new and desire to secure by 120 Letters Patent, is:—

1. The combination, with an outer or main cistern connected with the water supply, of an inner or supplemental cistern having a receiving opening, a connection between said 125 opening and the cistern supply pipe, an overflow edge or margin, and an outlet opening for the delivery of the water to the place of use.

2. The combination, with an outer or main 130

- cistern, of an inner or supplemental cistern, adapted, respectively, to deliver water into a water intake opening therefor near one side, a water overflow line or margin near the other side, and a curved bottom by which the water rushing in at the intake opening is guided and changed in its course from downward to upward and made to overflow the overflow margin.
3. In a cistern, an inner or supplemental vessel having intake passages in its side walls through which the water passes from the outer to this inner vessel, and provided with skirts which extend below the entrance of said passages into said inner vessel.
4. The combination, with an outer cistern, of an inner or supplemental cistern comprising a vessel having its walls curved opposite the supply pipe entrance, having a deflecting surface at its opposite side and having also skirted inflow passages, a supply pipe connected with said inner vessel and a discharge pipe also connected therewith, said pipes
5. The combination, with an outer or main cistern of an inner or supplemental cistern having a connection with the water supply, an overflow communication with the main cistern, an outlet for the delivery of the water to the place of use positioned in the supplemental cistern, and a cap extending over said outlet and below the same.
6. The combination, with an outer or main cistern of an inner or supplemental cistern having a connection with the water supply, an overflow communication with the main cistern, an outlet for the delivery of the water to the place of use positioned in the supplemental cistern, and a cap extended over said outlet and provided with one or more perforations opposite the outlet.

In testimony whereof I affix my signature.

JOHN P. PROBST.
